VINE PLANTER

W.H. Clarke England, 7310 Eastrest,
Austin, Tex. 78752

Filed Apr. 30, 1975, Ser. No. 572,972

Term of patent 14 years

Int. Cl. D11—62

U.S. Cl. D11—152

FIG. 1

FIG. 2

FIG. 3

FIG. 4

FIG. 5

FIG. 6

FIG. 7

FIG. 8

FIG. 1 is a perspective view of a vine planter showing my new design;

FIG. 2 is a top plan view thereof at a reduced scale;

FIG. 3 is a bottom plan view thereof;

FIG. 4 is a vertical cross-section taken on line 4-4 of FIG. 2;

FIG. 5 is a perspective view of a modified embodiment of the vine planter illustrated in FIG. 1;

FIG. 6 is a top plan view thereof, taken on a reduced scale;

FIG. 7 is a bottom plan view thereof; and

FIG. 8 is a vertical cross-section taken on line 8-8 of FIG. 6.

I claim:

The ornamental design for a vine planter, substantially as shown and described.
